UNITED STATES PATENT OFFICE

2,517,130

AUTOMATICALLY RELEASEABLE WORK CLAMP FOR SHIRT PRESSES

Edmund N. Neckel, Cincinnati, Ohio, assignor to
The American Laundry Machinery Company,
Cincinnati, Ohio, a corporation of Ohio

Application January 15, 1948, Serial No. 2,390

7 Claims. (CL 38—12)

1

This invention relates to work holders for use on garment pressing machines, and more particularly to a tail clamp for shirt presses.

One object of the invention is to provide improved work clamping or holding mechanism in which the clamping parts are actuated to move them to inoperative or work release position by a servomotor controlled by lowering movement of the press bed or buck as the press opens.

Another object is to provide improved clamping mechanism of the character described, including a valve device for controlling the servomotor which is reset to closed position by the operation of moving the clamp to release position and when so reset is ready for another work clamping operation.

Still another object is to provide improved work clamping mechanism of the character described in which the valve device itself serves as or actuates an abutment which prevents locking movement of the valve actuator to operating position until the clamp has been advanced to clamping position and the press has been closed and pressure applied to the work by elevating the bed or buck.

Another object is to provide improved clamping mechanism of the character described including means for so adjusting the parts as to insure accuracy and delicacy in operation and permit the clamp to be quickly moved to full open or work release position without vibration, jar or slamming effect.

Further objects of the invention in part are obvious and in part will appear more in detail hereinafter.

In the drawings, which represent one suitable embodiment of the invention, Fig. 1 is a rear elevation with certain parts broken away and in section, the dot-dash lines showing the clamp in open or work release position;

Fig. 2 is a diagrammatic view showing the press operating mechanism and the air circuits controlling its operation;

Fig. 3 is a similar diagram of the clamp operating servomotor and its controlling valve system;

Fig. 4 is an elevation looking toward the right-hand end of the press;

Fig. 5 is a sectional elevation, on the line 5—5, Fig. 4, showing an over-center spring;

Fig. 6 is an enlarged detail sectional view illustrating the valve plunger and its actuator;

Fig. 7 is an enlarged sectional view of the clamping and press mechanism, on the line 7—7,

2

Fig. 4, showing the press parts in preliminary closed position; and

Fig. 3 is a similar view, showing the press in full pressure position.

5 While the invention may be applied to various types of press and used for clamping any portion of a garment or other work piece, the drawings illustrate a form which embodies a tail clamp applied to a press closed by downward movement 10 of the head, with pressure applied by rising movement of the bed.

Referring first to Fig. 2, the press shown includes an upper pressing member or head 10 mounted upon one arm of a two-armed lever 11 pivoted at 12 in the frame 13 and a cooperating lower pressing member, bed or buck 14 supported on a pedestal 15 guided for vertical movement in the frame by depending pins 16 which slide in suitable frame bearings or guides, said 20 pedestal having a depending stem 17.

The head is closed by a fluid pressure servomotor 18, the piston rod 19 of which is connected to toggle links 20, 21, and is biased toward open position by a tension spring 22. The bed moves 25 down by its own weight and is elevated by a servomotor 23, the piston of which actuates a pivoted lever 24, an abutment on which lies beneath the lower end of the pedestal stem 17.

Movement of the two-hand control valves conventionally shown at 25, 26, causes air pressure to flow from the source (pipe 27) to motor 18, which straightens toggle links 20, 21, causing the head to move down to preliminary closed position, in which said links engage a yielding bumper device 28, compressing the spring thereof, and also actuating a two armed lever 29 which in turn operates valve 30. The latter opens a path for the flow of air pressure from the source to motor 23, the piston of which moves over and elevates the bed into full pressure relation with the head, compressing the padding and the work supported upon the bed. The two-hand valves 25, 26 now may be released, since the upward pressure of the bed holds the toggles straightened

35 and this action, in turn, maintains valve 30 open with consequent pressure in motor 23.

40 When release valve 31 is opened, it allows the air in motor 23 to evacuate. As the upward pressure of the bed on the head reduces, the spring bumper 28 breaks the toggle 20, 21, thereby permitting valve 30 to close, cutting off the flow of air to pressure cylinder 23. Thereupon spring 22 45 moves the head lever to press open position.

Thus, it will be observed, that all of the press operating air circuits or channels are cut off at

the moment the press begins to open. According to the present invention, the opening or lowering movement of the bed is utilized to control actuation of the work clamp by flow of air through a system or circuit separate or distinct from that which controls and operates the press, although air for the two circuits may originate in the same source. At least, neither circuit affects or interferes with the other.

The clamp itself, in this instance a tail clamp for a shirt, is an elongated metal band or strip 32 secured at its ends to long curved arms 33, one of which at the front of the press is provided with a knob or handle 34 by which the clamp may be manipulated. Said arms are secured to the outer ends of two aligned shaft members 35 (Fig. 4) mounted in spaced bearings 36 on brackets 37 carried by a support 38 which in turn is fastened to and moves up and down with a casting 39 mounted on the bed pedestal 15. The inner ends of the two shaft members are connected by a yoke 40 provided with a pin 41 which holds one end of a tension spring 42, the other end of which is attached to the lower end of support 38. A cross piece 43 on yoke 40 provides an abutment to engage a stop 44 to limit clamp opening movement. As the arms 33, shafts 35 and yoke 40 swing back and forth, spring 42 moves back and forth across dead center, biasing them first in one direction and then in the other.

One of shafts 35 at its outer end is provided with a rocker arm 45 pivotally connected to the piston rod of a servomotor 46 pivoted at 47 to the stationary press frame 13. Upon flow of pressure to this motor its piston moves over and turns shafts 35 to retract the clamp to open position. It is advanced to clamping position by manual effort applied to handle 34.

The same shaft 35, carries a second rocker arm 48 on which is pivotally mounted a block 49 slideable upon a rod 50 pivotally connected to the lower end of a valve actuating lever 51 pivoted to and depending from the casting 39, carried by the bed pedestal and provided with a roller 51a. A compression spring 52 surrounds rod 50 and lies behind block 49 and an adjustable rod collar 53. A second collar 54 is adjustable upon the rod on the other side of the block (Figs. 7 and 8).

Flow of pressure to and from motor 46 is controlled by a valve 55 conventionally shown in Fig. 3 and is regulated by the usual adjustable needle valve 56. Valve 55 is mounted upon the machine frame (Fig. 7) with its stem directly below a yielding plunger device shown in Fig. 6. This comprises a closed top cylinder 57 slideable in a support 58, a guide plug 59, a plunger 60 slideable therein and a compression spring 61 housed in the cylinder. Its purpose is to provide a self-adjusting, yielding connection between actuating arm 51 and the stem of valve 55, to accommodate variable travel of said arm for different adjustments of the parts. Motion of arm 51 in one direction is limited by engagement with casting 39 of an adjustable abutment screw stop 62.

The operation is as follows:

Figures 1, 2, 4 and 7 illustrate the parts in the positions they occupy when the press is preliminarily closed. That is to say, the operator, with the press open, has dressed a shirt upon the bed, has manually advanced the clamp to the clamping position shown, in which it is held by the bias of the over-center spring 42, and has actuated both of the two hand control valves 25, 26 to cause pressure to flow to motor 13 and close the press. However, toggles 20, 21 are not fully

straightened, and valve 30 has not yet been actuated, so that no pressure has yet passed to the servomotor 23, and the bed has not yet risen to apply full pressure to the work.

6 The plunger 57 lies in the path of advance movement of roller 51a on the lower end of lever 51, blocking its advance, so that compression spring 52 has been compressed and shortened, although the compression in this spring is insufficient to overcome the bias of spring 42. At the same time, arm 45 has moved clockwise in Fig. 1 and has retracted the piston of motor 46, evacuating that motor through valve 55, now open to exhaust.

15 Now, when toggles 20, 21 fully straighten and pressure flows through valves 30, 31 to motor 23, the piston of said motor moves over and elevates the bed into full pressure relation with the head as shown in Fig. 8. The clamping mechanism 20 rises with the bed, so that roller 51a moves up along the side of plunger 57 to a position above its upper end and then advances to the position shown in Fig. 8, where it lies directly above plunger 57.

25 When the pressing operation has been completed, the operator actuates exhaust valve 31, which evacuates the pressure from motor 23, permitting the bed to move down and thus return to its original position. During this motion 30 roller 51a engages the upper end of plunger 57 and depresses it, thus opening valve 55 and causing the flow of pressure to servomotor 46. As the piston of this motor begins to move the 35 clamp toward open position the slide block 49 on rocker arm 48 engages collar 54 on rod 50 and pulls the roller 51a off from plunger 57, allowing valve 55 to close, thus partially resetting the mechanism for another operation.

The position of collar 54 on rod 50 determines 40 the distance through which the piston of motor travels and consequently the amount of motion transmitted to the clamp and its supporting arms. If the collar is set back nearer toward the end of rod 50, motor 46 acts through or produces a 45 longer arc of clamp opening movement, while if adjusted nearer to block 49, an almost immediate closing of valve 55 occurs, with reduction in clamp travel. Collar 54 can be adjusted accurately to cause motor 46 to act just long enough 50 so that the momentum of the parts carries the clamp to its full open position without jar or 55 slamming effects. A slightly greater range of adjustment is made available by the adjustable stop screw 62, which allows positioning of arm 51 further forward or backward, as desired, to vary the amount of travel of roller 51a across the face of plunger 57 before it drops off from the plunger.

Of course, as soon as the bed has sufficiently 60 relieved the pressure upon the head, the bumper 28 breaks toggles 20, 21, opens the press, and evacuates motor 46, as before stated.

Now, with the press sufficiently open and the 65 clamp in open position, the operator removes the shirt from the press, dresses another upon it, and advances the clamp to clamping position. As before, this again compresses spring 52, but rising motion of the bed is necessary in order to permit the roller on the actuating arm 51 to reach its 70 operation position above plunger 57.

It will therefore be observed that in this arrangement, the clamping device is manually moved or adjusted to clamping position and is returned to its open position by its own servomotor. 75 This derives its pressure entirely independently

of the system which controls the operating movements of the press itself. Flow of pressure to the clamp actuating motor is controlled by a valve device sensitive to or affected by opening movement of the pressing members, and more particularly, in the press chosen for illustration, by the downward movement of the work supporting member or bed. However, the actuator for the controlling valve device for this purpose is cocked or moved to operating position as the result of both operator and machine operations. In other words, actuator 51 for the controlling valve 55 cannot reach its operating position, shown in Fig. 8, unless first the operator has manually advanced the clamp to clamping position and thus compressed spring 52, and the press bed has risen sufficiently to lift roller 51 to a level in which it can advance across the top of plunger 57 to its operating position.

The mechanism is of relatively simple form and requires no special attention by the operator, who is required only to advance the clamp to clamping position when the shirttails have been properly laid or arranged, and who then operates the press in the usual manner, the clamp automatically retiring to open position when the pressing operation is concluded. Sufficient adjustments have been provided to insure accuracy and proper timing and movement of all parts in operation.

Other advantages of the invention will be apparent to those skilled in the art.

What I claim is:

1. A garment press, comprising a frame, co-operating upper and lower pressing members both of which are movable with respect to the frame, means for depressing the upper member to close the press and for raising the lower member to apply pressure, a work clamp mounted for movement from open position to clamping position upon a garment between said members, a servomotor for retracting said work clamp to open position, a controller for said servomotor fixed with respect to the frame, and an actuator therefor carried by the lower pressing member, the location of said controller on said frame being such that lowering movement of said lower pressing member produces actuating contact between said actuator and said controller, whereby to cause said servometer to retract said clamp.

2. A garment press, comprising a frame, co-operating upper and lower pressing members both of which are movable with respect to the frame, means for depressing the upper member to close the press and for raising the lower member to apply pressure, a work clamp mounted for movement from open position to clamping position upon a garment between said members, a servomotor for retracting said work clamp to open position, a controller for said servomotor fixed with respect to the frame, an actuator therefor carried by and movable upon the lower pressing member, the location of said controller on the frame being such that lowering movement of said lower pressing member produces actuating contact between said actuator and said controller whereby to cause said servomotor to retract said clamp, said controller and actuator normally being out of operating relation with each other, and means operatively linked to said work clamp, and effective upon advance of the work clamp into clamping position for moving said actuator upon the lower pressing member into operating relation with said controller.

3. A garment press, comprising a frame, co-

operating upper and lower pressing members both of which are movable with respect to the frame, means for depressing the upper member to close the press and for raising the lower member to apply pressure, a work clamp mounted for movement from open position to clamping position upon a garment between said members, a servomotor for retracting said work clamp to open position, a controller for said servomotor fixed with respect to the frame, an actuator therefor carried by the lower pressing member, said controller being fixed on the frame in the path of movement of said actuator whereby lowering movement of said lower pressing member produces actuating contact between said actuator and said controller whereby to cause said servomotor to retract said clamp, and means operatively linked to said work clamp whereby to be raised and lowered with said work clamp and with said lower pressing member for establishing operative relation between said actuator and said controller when said lower pressing member is raised.

4. A garment press, comprising a frame, co-operating upper and lower pressing members both of which are movable with respect to the frame, means for depressing the upper member to close the press and for raising the lower member to apply pressure, a work clamp mounted for movement from open position to clamping position upon a garment between said members, a servomotor for retracting said work clamp to open position, a controller for said servomotor fixed with respect to the frame, and an actuator therefor carried by and movable with the lower pressing member, the location of said controller on said frame being such that lowering movement of said lower pressing member produces actuating contact between said actuator and said controller, whereby to cause said servomotor to retract said clamp, said actuator being movable on the lower pressing member into or out of operative relation with the controller.

5. A garment press, comprising a frame, co-operating upper and lower pressing members both of which are movable with respect to the frame, means for depressing the upper member to close the press and for raising the lower member to apply pressure, a work clamp mounted for movement from open position to clamping position upon a garment between said members, a servomotor for retracting said work clamp to open position, a controller for said servomotor fixed with respect to the frame, an actuator therefor carried by and movable with the lower pressing member, the location of said controller on said frame being such that lowering movement of said lower pressing member produces actuating contact between said actuator and said controller, whereby to cause said servomotor to retract said clamp, said actuator being movable on the lower pressing member into or out of operative relation with the controller, and biasing means operatively linked to said work clamp whereby to be moved by movement of said clamp, and contactable with and effective upon said actuator for applying bias to said actuator.

6. A garment press, comprising a frame, co-operating upper and lower pressing members both of which are movable with respect to the frame, means for depressing the upper member to close the press and for raising the lower member to apply pressure, a work clamp mounted for movement from open position to clamping position upon a garment between said members, a servo-

75

motor for retracting said work clamp to open position, a controller for said servomotor fixed with respect to the frame, an actuator therefor carried by and movable with the lower pressing member, the location of said controller on the frame being such that lowering movement of said lower pressing member produces actuating contact between said actuator and controller whereby to cause said servomotor to retract said clamp, biasing means operatively linked to said work clamp whereby to be moved by movement of said clamp, and contactable with and effective upon said actuator for applying bias to said actuator, whereby to tend to advance said actuator into operative relationship with the controller, restraining means for preventing such advance, said restraining means being fixed to the frame whereby movement of said lower pressing member causes relative movement between said restraining means and said actuator, said restraining means being so positioned with respect to said actuator that advance of said actuator into registry with said controller is permitted only when said lower pressing member is moved toward garment pressing position.

7. A garment press, comprising a frame, cooperating upper and lower pressing members both of which are movable with respect to the frame, means for depressing the upper member to close the press and for raising the lower member to apply pressure, a work clamp mounted for movement from open position to clamping position upon a garment between said members, a servomotor for retracting said work clamp to open position, a controller for said servomotor fixed with respect to the frame, an actuator therefor carried by and movable with the lower pressing

member, the location of said controller on the frame being such that lowering movement of said lower pressing member produces actuating contact between said actuator and controller whereby to cause said servomotor to retract said clamp, biasing means operatively linked to said work clamp whereby to be moved by movement of said clamp, and contactable with and effective upon said actuator for applying bias to said actuator, whereby to tend to advance said actuator into operative relationship with the controller, restraining means for preventing such advance, said restraining means being fixed to the frame whereby movement of said lower pressing member causes relative movement between said restraining means and said actuator, said restraining means being so positioned with respect to said actuator that advance of said actuator into registry with said controller is permitted only when said lower pressing member is moved toward garment pressing position, and means fixed to said work clamp to withdraw said actuator from operative relation with said controller when said work clamp is retracted.
